LOUVER CONSTRUCTION

Andrew B. Madson, Los Angeles, Calif.

Application June 20, 1947, Serial No. 755,952

9 Claims. (Cl. 20—63)

1

This invention relates to louvres, such as are often used to shield or screen an opening through which it is desired to prevent direct vision while permitting restricted passage of light and air.

It is an object of this invention to provide an improved form of louver which is adapted to be fabricated in a simple and economical manner.

It is another object of this invention to provide a louver so arranged as to simplify and facilitate the installation of the slats or louver boards.

It is still another object of this invention to provide an improved method of fabricating a louver.

This invention possesses many other advantages and has other objects which may be made more easily apparent from a consideration of several embodiments of the invention. For this purpose there are shown a number of forms in the drawings accompanying and forming part of the present specification. These forms will now be described in detail, illustrating the general principles of the invention; but it is to be understood that this detailed description is not to be taken in a limiting sense since the scope of the invention is best defined by the appended claims.

In the drawing:

Figure 1 is an elevation of a shutter or the like, comprising a louver embodying the features of the invention;

Figure 2 is a fragmentary elevation on an enlarged scale, illustrating a step in fabricating the louver of Figure 1;

Fig. 3 is a fragmentary vertical section, taken substantially as indicated by line 3—3 of Fig. 2, on a further enlarged scale;

Figure 4 is a cross section taken substantially as indicated by line 4—4 of Figure 2;

Figure 5 is a cross section corresponding to Figure 4, but showing the completed louver;

Figure 6 is an elevation showing an alternative method of fabricating a louver; and

Figure 7 is a detail section, taken substantially as indicated by line 7—7 of Figure 6.

As is well understood, a louver commonly comprises a plurality of spaced horizontally extending vertically inclined slats or louver boards supported by engagement respectively of their opposite ends in recesses provided in a pair of vertically extending side members. Such side members for example, may be the stiles of a shutter, or of a door or window frame, in which case the louver becomes an integral part of the door, shutter or the like; or the side members may be the vertical elements of a louver frame, adapted for mounting the louver as a unit in a wall opening or in an opening provided in a door or window

2

sash. The present invention contemplates the provision of a novel arrangement of such side members whereby the installation of the slats or louver boards is greatly facilitated.

Referring to the drawings, Figure 1 shows a louver as forming an integral part, for example, of a shutter structure wherein the frame, generally indicated by the numeral 1, serves to support the slats or louver boards 2. The frame 1 comprising the stiles or side members 3 and 4, and the rails or horizontal members 5 and 6, could equally well be that of a door or window sash or merely a supporting frame.

As shown in Figures 3 and 5, each of the stiles 15 3 and 4 respectively has a plurality of inclined spaced parallel recesses 7 and 8 cooperating to mount the louver boards or slats 2. To facilitate the placing of the slats 2 in their respective recesses 7 and 8, corresponding portions of the 20 facing edges of the stiles 3 and 4 have cut out portions or rabbets 3-c and 4-c extending the full length thereof. As clearly shown in Figures 3 and 4, the depth of these rabbets 3-c and 4-c is less than that of the intersected recesses 7 and 8. Furthermore, the rabbets extend only for part 25 of the length of the recesses.

The arrangement is such that by maintaining the stiles or side members 3 and 4 in parallel relationship with the recesses 7 and 8 opposite 30 each other, and the members so spaced that the slats 2 can pass freely between the rabbets or cut-out portions 3-c and 4-c, the slats may be easily inserted in their respective pairs of recesses 7 and 8. Then by reducing the spacing 35 between the members 3 and 4 the slats will be confined in these recesses.

Where the various frame members as the stiles or side members 3 and 4 and the rails or top and bottom members 5 and 6 are of suitable 40 size as in the form of Figs. 1 to 5, the members may be joined in such manner that the side members are adapted to be maintained in spaced parallel relation without the need of any supplemental structure. For example the rails 5 and 45 6 may be provided with tenons as 10 and 11 adapted to engage respectively the mortises 12 and 13 formed in the side members 3 and 4.

From an inspection of Figs. 2, 3 and 4 it will be apparent that one of the side members such 50 as 3, may be spaced a sufficient distance from its final position to accommodate the slats 2 between the rabbets 3-c and 4-c. Thus the slats 2 may be inserted readily into those parts of the recesses 7 and 8 which are of full depth (see 55 particularly Figure 4), the slats being held properly placed thereby. After all of the slats

2 have inserted, the member 3 is moved to its final position, causing the slats 2 to enter additionally those parts of the recesses 7 and 8 of reduced depth (see Figure 5). This secures the slats 2 in the frame 1, and the side member 3 is appropriately fixed to the rails 5 and 6.

It may be desirable to provide a lighter frame for mounting the louvre boards. Such a frame is shown partially completed in Fig. 6 and comprises side members 15 and 16 and end members 17. Since these members are quite thin, they are to be connected by mitered joints at the corners of the frame. The side members 15 and 16 are provided as before with recesses as 18 (Fig. 7) for mounting the louvre boards 2, these recesses being intersected by a rabbet 19 to permit insertion of the louvre boards 2.

To maintain the frame members appropriately positioned for insertion of the boards 2, a jig 20 may be provided defining a rectangular space for accommodating the frame. As clearly shown in Fig. 6, the width of the jig 20 is such that the side members 15 and 16 are so spaced as to accommodate the slats 2 between the rabbets 19 and permit the slats to be placed in the recesses 18.

After placement of the slats, the side member 15 is secured in its final position on the end members 17, the slats 2 being retained in the recesses 18, as before.

I claim:

1. In a louvre construction: means forming a pair of spaced parallel members having respectively a plurality of opposed recesses; and louvre boards mounted respectively in pairs of opposed recesses, each of said members having a cut-out portion extending along an edge thereof and intersecting the recesses therein at points intermediate their depth, said members being positioned with the cut out portions in facing relation, the space between the cut-out portions being less than the length of the louvre boards.

2. In a louvre construction: a member adapted to form an element of a supporting frame for the louvre boards, having a plurality of inclined spaced parallel louvre board receiving recesses, as well as a rabbeted edge intersecting said recesses at points intermediate their depth.

3. In a louvre construction: a frame comprising a pair of spaced parallel side members and a pair of end members, said side members having opposed louvre board accommodating recesses; there being a rabbet along an edge of each side member reducing the depth of a part of each recess therein, said rabbets being in facing relation, and means joining at least one side member to said end members in a manner to permit initial spacing of said side members to accommodate the louvre boards between said rabbets, and thereafter at reduced spacing to confine said boards in said recesses.

4. In a louvre construction: a frame comprising a pair of spaced parallel side members and a pair of end members, said side members having opposed louvre board accommodating recesses; there being a rabbet along an edge of each side member reducing the depth of a part of each recess therein, said rabbets being in facing relation, and means joining at least one side member to said end members in a manner to permit initial spacing of said side members to accommodate the louvre boards between said rabbets, and thereafter at reduced spacing to confine said boards in said recesses, said means comprising a

tenon on each end member, and mortices in said side member cooperating respectively therewith.

5. In a louvre construction: a pair of side members and a pair of end members adapted to form a rectangular frame, there being opposed louvre board accommodating recesses in said side members; there being a rabbet along an edge of each member, said edges being in facing relation; and means including a pair of spaced parallel surfaces adapted to cooperate with said side members to maintain said members in substantial parallelism while so spaced as to permit the louvre boards to pass between said rabbets into said recesses.

15 6. In a louvre construction: a pair of side members and a pair of end members adapted to form a rectangular frame, there being opposed louvre board accommodating recesses in said side members; there being a rabbet along an edge of each member, said edges being in facing relation; and means forming a supporting framework having pairs of opposed surfaces inclosing a rectangular space, the surfaces of one of said pairs positioning said end members, the surfaces of the other pair spacing said side members to permit the louvre boards to pass between said rabbets.

20 7. The method of constructing a louvre which comprises: rabbeting an edge of each side member of a louvre frame to reduce the depth of the louvre board receiving recesses therein for a portion of the length of said recesses; spacing said members to accommodate the louvre boards between said rabbets; placing said boards in their respective recesses; and reducing the spacing to confine said boards in said recesses.

25 8. The method of constructing a louvre which comprises: forming a rabbet along an edge of each side member of a louvre frame to intersect the louvre board receiving recesses in said member at a point intermediate their depth, said edges being in facing relation; maintaining said members in parallel relation and so spaced as to permit passage of louvre boards between said rabbets into the opposing recesses; placing said boards in said recesses; causing relative movement between said members to reduce the space and confine the boards in their respective recesses; and securing said members in reduced spaced relation.

30 9. In a louvre construction: a pair of spaced parallel members having respectively opposed louvre board accommodating recesses; and louvre boards mounted respectively in pairs of opposed recesses, each of said members having a pair of spaced parallel sides as well as an edge, said edges being so formed as to intersect the sides of the respective members in offset relation, forming in each recess, portions of different depths, said edges being in facing relation, with recess portions of corresponding depth opposed, the distance between said edges adjacent the recessed portions of reduced depth being less than the length of said louvre boards.
